COOLING SYSTEM

Daniel Pica, Chicago, Ill., assignor to Frank Kemptner, Chicago, Ill., as trustee

Application July 9, 1938, Serial No. 218,441

5 Claims. (CL 123—173)

This invention has to do with an air cooling system for cylinders. It is particularly adapted to internal combustion motors using reciprocating and rotatory pistons, an example of which is disclosed in my co-pending application, Serial No. 81,091 filed May 21, 1936. It may equally well be used, however, with any internal combustion engine having the conventional reciprocating pistons, with air compressors, or wherever cooling

10 becomes a consideration.

As is well known, air cooling systems have long been in use for internal combustion engines, although for the most part, in the automobile field, they have been superseded by circulatory liquid systems. As the size and the horsepower of an engine is increased, a point is reached in the conventional air cooling system, even when used in airplanes, where it is impossible adequately to cool the engine. Under such circumstances it 20 becomes necessary to use a circulatory liquid system which carries with it disadvantages in cost, added weight per horsepower of from 20 to 45 per cent., and added bulk.

My invention makes it possible to air cool an 25 internal combustion engine of any size irrespective of the weight or horsepower involved, and in any type of engine, whether the cylinders be disposed radially, are opposed, or are in the conventional series V type, or otherwise, of the automobile engine. The same is equally true of any 30 type of compressor.

In the accompanying drawing, Fig. 1 is a plan view of the cylinder head of my engine. Fig. 2 is a view along the line 2—2 of Fig. 1, partly in 35 section and partly in side elevation. Fig. 3 is a view along the line 2—2 of Fig. 1, partly in section and partly in side elevation, the cylinder however, containing a piston of the conventional reciprocating type.

40 *Rotatory engines*

In the preferred application of my invention to an engine having a reciprocating and rotatory piston, Fig. 2 shows a cylinder 10 having a cylinder head 11. Within the cylinder is a piston 12 having a skirt 13 adapted to engage closely a slot or chamber 14 between the well of the cylinder head 11 and the cylinder wall 10. In Fig. 2 the piston 12 is shown at the bottom point of its 50 stroke on an explosion. In the side of the cylinder wall 10 is a cam track 15 following the path of a sine curve, being semi-circular in cross section. The curve of the cam track is shown by the dotted lines on Fig. 2. On opposite sides of the piston 55 12 are a pair of semi-spherical depressions 16, 16

having a radius similar to the maximum radius of the cam track 15. Between the cam track 15 and the semi-spherical depressions 16, 16 in the piston is a pair of cam followers 17, 17 sized to fit closely in the depressions 16, 16 and the cam track 15. In the base of the piston 12 are a pair of cylindrical wells 18, 18 which are snugly engaged by a pair of cylindrical rods 19, 19 fixed to a fly wheel 20. The piston 12 is free to move upward and downward upon the rods 19, 19 thus 10 translating a rotatory and reciprocating motion of the fly wheel 20 and the drive shaft 21.

Means for admitting fuel and emitting exhaust are found in the orifice 22 in the piston skirt 13 and are more particularly explained in my co-pending application Serial No. 81,091. It will be understood that the orifice 22 is traveling the path of a sine curve during a cycle of the engine. At suitable points along the path of this curve, the orifice 22 engages slots 23, 23 shown in the dotted lines on Fig. 2, in the cylinder wall 10, through which fuel is admitted or the exhaust drawn off.

It will further be understood that the necessity for cooling an engine arises from the intense 25 heat created by the explosion of the fuel at the top of the stroke. At this position on my engine, the bottom of the piston well is in juxtaposition to the gap on the spark plug 25 and the skirt of the piston completely fills the annular slot 14. 30 When the explosion occurs the piston is given a downward impulse and the skirt 13 begins to recede in the slot or chamber 14. As the slot or chamber 14 is connected with the ambient atmosphere through orifices 24 in the cylinder head 11, 35 air is sucked into the slot with the result that a cooling medium having normal atmospheric temperature is introduced into very close proximity with the seat of the greatest amount of heat. On its up stroke, the skirt 13 rises to fill the annular 40 slot or chamber 14 expelling the heated air through the orifices 24 and drawing in on the suction stroke, a new supply of air having an atmospheric temperature. Thus it will be seen that in a four-cycle engine, air having an atmospheric temperature is twice circulated in close proximity to the point of explosion at the top of the cylinder, which has the effect of completely cooling the engine to the same or a greater degree than the circulation of water in the 50 cylinder jacket. In a two-cycle or intermittent type of engine, air is drawn into the chamber 14 on every reciprocation of the piston 12. It will further be seen that whereas the water in a circulatory system quickly reaches a temperature in 55

close proximity to the boiling point, which is maintained throughout the operation of the engine, the air which is used to cool my cylinder is at an atmospheric temperature.

5

Reciprocating engines

The application of my invention to a conventional engine is shown in Fig. 3, the piston 12 being provided with a skirt 13 adapted to engage 10 an annular slot or chamber 14 in the top of the cylinder head. Said engine also comprises a wrist pin 26, a connecting rod 27, a crank shaft 28 and a crank case 29. Fuel is admitted through the registration of orifices 30, 30 with slots 31, 31, 15 shown in dotted lines in the cylinder wall, said slots being connected by passageways with conventional poppet valves, not shown. The only difference in operation between the engines shown in Figs. 2 and 3 arises from the fact that in the conventional engine shown in Fig. 3, the piston 12 does not rotate. The oscillation of the skirt 13 in the slot or chamber nevertheless produces the result of pumping in a supply of air having 20 atmospheric temperature on each down stroke and expelling it on each up stroke to keep the engine in such a condition that it will operate 25 without any other cooling system.

In both Figs. 2 and 3 I have shown fins 32 on 30 the outside wall of the cylinder 10. These form no part of my invention, and it is to be understood that my cooling system will cool an engine for an indefinite period without assistance of fins on the outer wall of the cylinder, or the circulation of ambient atmosphere therethrough.

35

Compressors

It is to be understood of course that the application of cooling problems is not confined to internal combustion engines where heat is created 40 as the result of an explosion, but may also arise in compressors where heat is created as a result of the compression of gases. While I have not shown the application of my invention to a compressor in the drawing, any one skilled in the art will readily perceive how a compressor can 45 be designed with a sleeved piston, the sleeve moving backward and forward in an annular slot or chamber which is connected by orifices or passageways with the ambient atmosphere. The 50 function of the sleeve and the slot or chamber is the same whether it be associated with an engine or with a compressor.

Independently actuated air pumps

55 It is further to be understood that the annexed drawing is simply illustrative of my cooling system. While the devices disclosed in Figs. 2 and 3 represent the simplest answer to the problem, wherein the piston performs the dual function of receiving and transmitting the energy of an explosion to a drive shaft, and of circulating the 60 ambient atmosphere in a chamber in close proximity to the seat of the explosion, means, independent of the piston, may be used for circula-

tion of air, and the circulation of air need not necessarily be confined to the region of the annular slot or chamber 14 shown in Figs. 2 and 3, but air may further be circulated through passageways in the cylinder jacket 10, or around the 5 valves if that be desired.

Having fully described my invention, I claim:

1. In a cooling system, the combination of a cylinder having an annular chamber between the cylinder head and the cylinder wall, a piston having a skirt adapted to reciprocate in said annular chamber, and a continuous connection between said annular chamber and the ambient atmosphere, the location of said chamber and connection being such with reference to said cylinder head and wall that upon the retrogression of said piston from the top of its stroke there is approximately immediate contact of the ambient atmosphere with the surface of both said cylinder head and wall within said chamber, said surface of contact increasing as said piston retrogresses. 10

2. In a cooling system, the combination of a cylinder having an annular chamber between the cylinder head and the cylinder wall, a piston having a skirt adapted to reciprocate and rotate in said annular chamber, and a continuous connection between said annular chamber and the ambient atmosphere. 15

3. In a cooling system, the combination of a cylinder having explosion means, an air chamber 30 within said cylinder in close proximity to said explosion means, said air chamber being directly and continuously connected by a passageway with the ambient atmosphere, and reciprocating and rotating means to fill said chamber with air and 35 exhaust the same following an explosion in said cylinder.

4. In a cooling system, the combination of a cylinder, a piston in said cylinder, a source of heat developed by the movement of said piston in said 40 cylinder, an air chamber within said cylinder continuously and directly connected with the ambient atmosphere in close proximity to said source of heat, and reciprocating and rotating means connected with said piston, so constructed and arranged that said chamber is filled with turbulent air and exhausted during the movement of said piston in said cylinder. 45

5. In a cooling system, the combination of a cylinder having an annular chamber between the cylinder head and the cylinder wall, a piston having a skirt adapted to reciprocate and rotate in said annular chamber, and a continuous connection between said annular chamber and the ambient atmosphere, the location of said chamber and connection being such with reference to said cylinder head and wall that upon the retrogression of said piston from the top of its stroke there is approximately immediate contact of the ambient atmosphere with the surface of both 50 said cylinder head and wall within said chamber, said surface of contact increasing as said piston retrogresses. 55

DANIEL PICA.
